(57) CLAIM

The ornamental design for a bra, as shown and described.

DESCRIPTION

FIG. 1 is a front view of a bra, showing my new design; FIG. 2 is an exploded front view thereof; FIG. 3 is a front view of the bra shown in an alternate configuration in an environment of use on a mannequin; FIG. 4 is a front view of the bra shown in a second alternate configuration of use in an environment on a mannequin; FIG. 5 is a perspective view of the bra shown in a third alternate configuration in an environment of use on a mannequin; FIG. 6 is a perspective view of FIG. 4; FIG. 7 is a left side view thereof; FIG. 8 is a right side view thereof; FIG. 9 is a rear view of FIG. 3; FIG. 10 is a rear view of FIG. 6; FIG. 11 is a rear view of FIG. 5; and, FIG. 12 is a rear view of the bra shown in a fourth alternate configuration in an environment of use on a mannequin. The broken lines in the figures show portions of the bra which form no part of the claimed design. The additional broken lines showing a mannequin are to show environment and form no part of the claimed design.

1 Claim, 12 Drawing Sheets
